Original application September 17, 1940, Serial
No. 357,140. Divided and this application Sep-
tember 10, 1941, Serial No. 410,287

3 Claims. (Cl. 296—44)

This invention, which is a division of our co-pending application Serial No. 357,140, relates to a mounting for the windows of motor vehicles and is applicable to other types of sliding closures, such as doors. The windows of automobiles are not all of standard shape and dimension, some having their upper or vertical edges cut on a bias to conform to the streamlined shape of the vehicle body. This bias has the disadvantage of reducing the extent of engagement of one vertical edge of the window in its guiding channel. Consequently the glass has a tendency to cant and bind in its guiding support.

The object of the present invention is to provide a window or closure mounting which will be efficient and free from binding action. The invention further has for its object to provide a guiding support for the window which support can be practically disposed within the lower curved portion of the usual automobile door to increase the effective support for the relatively short vertical edge portion of a bias cut glass panel.

In the accompanying drawing

Fig. 1 is a phantom view of a portion of an automobile body showing the present invention incorporated therein;

Fig. 2 is a vertical sectional view through the lower portion of the door showing the window guiding support in its lower position;

Fig. 3 is a similar view through the medial portion of the door depicting the guiding support in its elevated position; and

Fig. 4 is a detailed sectional view about on line 4—4 of Fig. 1.

Referring more particularly to the drawing, the improved mechanism has been depicted, for the sake of illustration, in connection with the vertically sliding type of window which term is inclusive of doors and other sliding closures having similar mountings. This window is designated by the numeral 1 which is guided vertically in channel ways 2 and 3, and where the window panel tapers off toward one side, as illustrated in Fig. 1, a bracket part 4 is secured to the carrier or frame 5 for the panel to extend the effective bearing in the particular guideway.

To insure against the glass tilting or binding in its guideways a bracket arm 6 extends downwardly from the bracket extension 4 and carries a pair of rollers 7 for running along a fixed track 8. By reason of the contour of the modern motor vehicle, wherein the lower portion of the door curves inwardly, the fixed track 8 is also given a conforming curvature and consequently the

bracket arm 6 is provided of resilient material so as to readily yield and follow the track 8 without impairing the guiding and steadyng influence thereof on the vertically slidable glass.

5 The window glass is elevated by means of a fluid motor, preferably one utilizing an air pressure differential in which the low pressure influence of the intake manifold may be used. As illustrated, the motor comprises a cylinder 9 and 10 a piston 10. The piston rod 11 is operatively connected to the window to elevate and lower the same as desired. The connection disclosed embodies a bell crank lever 13 pivoted on a stud 14 carried by a bracket 15, and to this stud is 15 fixed one end of a convolute spring 16 to counter-balance the sash, the opposite end of the spring being fixed to the sash connected arm of the bell crank. The cylinder is given free pivotal or yielding support on a bracket 17 by a short spring 20 leaf 18 which permits the opposite end of the cylinder with its protruding piston rod to swing in a vertical plane for accommodating the arcuate travel of the pivotal connection 19 between the free end of the piston rod and the other 25 arm of the bell crank lever incidental to the sliding motion of the piston. A steadyng influence is exerted on the outer end of the cylinder during this swinging movement by a fixed guide finger 20.

30 The fluid motor is connected to a source of operating pressure by conduit 21 in which is interposed a pair of valves 22 and 23 for controlling the communication through branch conduits 24 and 25 whereby the required pressure differential 35 may be applied to the piston for rocking the bell crank lever 13 to adjust the window vertically in the guideways 2 and 3.

40 By reason of the bias cut one vertical edge 26 is reduced in length considerably and therefore there is an increased tendency on the part of the glass panel 1 to become tilted within the guideways 2 and 3 and produce an objectionable binding. It is the purpose of the bracket extension 4 to effectively increase the marginal edge portion 26 of the glass panel so as to provide a more substantial guiding support for the panel against becoming canted within its window guideway. The extent of the guide arm 6 also increases the stabilizing effect of this guiding support by reason of its downward reach into the window well of the door where its free end engages the track. The bracket arm 6 may be formed of a spring strap or leaf which permits the roller carriage 7 readily following the curvature of the track but resists flexing in a plane extending lengthwise of

the vehicle. By reason of its flexible character the supporting arm 6 may be possessed of the desired length to afford substantial support for the adjacent preshortened window portion. Consequently the lower portion of the track 8 may extend downwardly into the lowermost portion of the door recess or well so as to give support to the window in all adjustments thereof.

While the foregoing description has been given in detail it is obvious that the principles of the invention herein disclosed may be incorporated in other physical embodiments without departing from the spirit of the present invention or from the scope defined in the appended claims.

What is claimed is:

1. Operating mechanism for the door windows of a motor vehicle having an inwardly curved side wall design, comprising in combination with a vertically slideable window panel having one vertical side shorter than the other, straight guideways for the vertical sides, means for actuating the window panel, a guide carriage, a bracket arm fixed at one end on and depending from adjacent the shorter vertical side of the window and on its free end supporting the carriage, and a fixed track on which the carriage operates, said track being curved substantially to conform to the wall curvature with the straight guideways extending substantially tangentially from the curved track, the depending bracket arm being flexible laterally in the direction of track curvature to move the carriage in conformity to the curvature thereof.

2. In a motor vehicle window mounting for guiding the window into and out of a window well in the wall structure of a motor vehicle, a pair of straight channeled rails extending downwardly into the well, a window panel having one vertical side shorter than the other and slidably mounted in the channels of the rails, a bracket connected to the panel adjacent the shorter vertical side

thereof and having an arm depending downwardly into the well, the wall structure of the vehicle adjacent the lower portion of the well curving inwardly, a curved track fixed adjacent the path of the outer end of the bracket arm and following substantially the curvature of the wall structure in substantially tangential relation to the channeled rails, and track engaging means carried at the outer end of the bracket arm and riding upon the track to support the shorter vertical side of the window panel against tilting in the channeled rails, the bracket arm being arranged for flexing laterally to follow the track curvature and being braced against flexure at right angles to the curvature whereby to guidingly support the window panel in its sliding movement.

3. In a motor vehicle window mounting for guiding the window into and out of a window well in the wall structure of a motor vehicle, a pair of straight guide rails extending downwardly into the well, a window panel having one vertical side shorter than the other and slidably mounted on the rails, a bracket connected to the panel adjacent the shorter vertical side thereof and having a spring arm depending downwardly into the well, the wall structure of the vehicle adjacent the lower portion of the well curving inwardly, a curved track fixed adjacent the path of the outer end of the bracket arm and following substantially the curvature of the wall structure in substantially tangential relation to the rails, and track engaging means carried at the outer end of the bracket arm and riding upon the track to support the shorter vertical side of the window panel against tilting on the rails, the track engaging means being arranged for moving laterally to follow the track curvature during flexing of the bracket arm whereby to guidingly support the window panel in its sliding movement.

ANTON RAPPL,
ERWIN C. HORTON.
